UNITED STATES PATENT OFFICE.

JOHN WEIRICK, OF MIFFLINBURG, PENNSYLVANIA.

HARNESS.

SPECIFICATION forming part of Letters Patent No. 276,105, dated April 17, 1883.

Application filed January 26, 1883. (No model.)

To all whom it may concern:

Be it known that I, JOHN WEIRICK, of Mifflinburg, in the county of Union and State of Pennsylvania, have invented certain new and useful Improvements in Harness; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to improvements in that class of inventions known as "harness," and to this end it consists in novel means for connecting and fastening the trace to the tug, the tug to the hame, the combination of the saddle-band with a holdback-strap and trace-carrier, a box-loop slide or keeper, and other details of construction, all of which will be hereinafter more particularly described.

In the drawings, Figure 1 represents a view of one side of a harness, showing the use of my improvements as employed therewith. Fig. 2 is a perspective view of the hame screw-clip or tug. Fig. 3 is a perspective view of the adjustable screw-buckle. Fig. 4 is a view of a screw trace-carrier. Fig. 5 is a side view of the screw-shaft-bearer buckle. Fig. 6 is a perspective view of the box-loop slide. Fig. 7 is a perspective view of the screw-buckle as in separate parts. Fig. 8 is an edge view of a trace, tug, buckles, and box-loop attached to the hame-link. Fig. 9 is a view in perspective of a part of a shaft with portion of band.

A represents the back-strap; B, a portion of saddle; C, the trace. D is the hip-band, and d a part of a hame.

In a link in the hame d is fitted a hooked end of the hame screw-clip a, and said end bent under and brought up through a slot, a', in said clip. The end of the trace-tug C', having eyelets, fits onto the screw a'' of the clip, and is held or retained thereon by screwing on the screw-cap a''', which has an arched turning piece to enable it to be screwed on tightly. The trace-tug, being double, forms a loop, in which is held the adjustable screw-buckle through a slotted projection, b', thereon. This buckle is formed of a piece of metal having the said slotted projection b', and on the sides of this piece are upright extensions b'', to

which are pivotally hinged two ends of a plate, b''', having therein a slot, 1, for fitting over the screw-tongue, and a slot, 3, for holding a strap when desired. Over this loop formed by the trace-tug, within which is held the adjustable screw-buckle, is a box-loop slide or keeper, c, being different from ordinary box-loop slides in that it is provided with metallic holders or fasteners c'. The difficulty experienced heretofore in securing or stitching a keeper to any part of a harness has been that it is hard to sew it on the strap, it requiring great expense of labor and time to accomplish. 65 By my improvement, to which I have given the term "slide," it is done—viz., as in Fig. 8. Where the part C' of the tug is doubled, it is slipped through the fastener, which is on one end of the slide. The double strap on which it is placed is sewed between the ends of the slide. Then the end of the strap is slipped through the other holder and the sewing continued, and is thus held in position by the metallic fastenings. The trace is fitted onto the 75 screw-tongue of the adjustable buckle, the free end being held by the slide, and also on the screw-tongue of said buckle is fitted the end of the portion of the saddle, leaving enough projecting with which to secure the girt-band. 80 (Not shown.) Then by pushing down over these the plate b''' and screwing on the screw-cap 4, (which is the same in construction as screw-cap a'''), the buckling is made secure and strong, and the tighter the screw-cap is 85 screwed on the less strain there is upon the tongue, the compression of the straps made by the buckle acting as a relief thereto. Instead of the screw-buckle, as shown in Fig. 3, being used, the kind b shown in Fig. 7 is an equally 90 secure and advantageous buckle, it being a modification of the other, the difference being that its parts are separate, and it is intended to be used on the back-strap, if desired. The hip-band D is turned and buckled to form a 95 loop for carrying the trace, and up through eyelets in the back-strap, at the part where the hip-band crosses, extends a screw-tongue formed on a circular piece of metal, e, a leather loop, f, being secured on the back-strap at this 100 part, through which the hip-band and a holdback-strap pass, the purpose of which loop and holdback-strap will be described herein-after. On the screw-tongue on the plate e is

screwed a sort of cockeye, *g*, as shown in Fig. 4, said cockeye being shaped at the top like an anchor, said device being entitled the "screw-trace carrier," and serves to hold the back end 5 of the traces on when they are unhitched from the single-tree.

In Fig. 9, *H* is a shaft which is held up by a shaft-carrier, *I*, secured onto the girth and saddle-strap *i* by a device similar to the screw-buckle heretofore described, except that it is bent around the ring, but is provided with a screw-tongue running through the strap, which is held on by the screw-cap.

G is a holdback-strap attached to the saddle-strap, and runs through the loop *f* on the back-strap. It is intended to be utilized in light harness instead of the ordinary breeching-strap, and with double harness serves to prevent the collars from running up on the 15 horses' necks when descending incline planes. The loop *f* on the back-strap has the screw-tongue passing up through it, onto which the cockeye is screwed, and it is thus turned into a double loop, the hip-band working through 20 it on one side of the cockeye and the holdback-strap on the other.

Having described my invention, what I claim is—

1. In a harness, the combination of the trace, 30 having the box-loop slide secured thereon in the manner described, with the hame screw-

clip or tug and adjustable screw-buckle, substantially as set forth.

2. In a harness, the saddle-band having secured thereto by the screw-buckle a holdback-strap, in combination with the back-strap provided with the double loop, and the screw trace-carrier, as described. 35

3. In a harness, the combination of the trace and tug thereof with the screw-buckle and 40 cap herein described, said buckle being of two parts pivotally connected and slotted, and adapted to be adjusted to any thickness of strap, substantially as and in the manner set forth.

4. In a harness, the combination of the trace-tug and hame thereof with the screw-clip and 45 cap herein described, said device adapted to hold and connect the same, substantially as and in the manner shown.

5. In a harness, the back-strap having the loop, the combination of the metal plate having a screw-tongue fitting through said loop, as described, with the anchor-shaped cockeye and trace, substantially as set forth. 50

In testimony that I claim the foregoing as my own I affix my signature in presence of two witnesses.

JOHN WEIRICK.
